UNITED STATES PATENT OFFICE.

WILLIAM E. WEBB, JR., OF LARCHMONT MANOR, AND GEORGE L. CLOSE, OF MOUNT VERNON, NEW YORK, ASSIGNEES TO CHURCH, WEBB & CLOSE, INC., OF NEW YORK, N. Y., A CORPORATION OF NEW YORK.

TRENCH-HELMET.

1,286,854.

Specification of Letters Patent.

Patented Dec. 3, 1918.

Application filed January 31, 1918. Serial No. 214,766.

To all whom it may concern:

Be it known that we, WILLIAM E. WEBB, Jr., and GEORGE L. CLOSE, citizens of the United States, residing in Larchmont Manor and Mount Vernon, respectively, in the county of Westchester and State of New York, have invented certain new and useful Improvements in Trench-Helmets, of which the following is a specification.

10 This invention relates to improvements in trench helmets especially adapted for soldiers' use, and designed to be used in connection with metal shrapnel helmets or other outside headgear.

15 The main object of the invention is to provide a warm trench helmet or hood adapted to cover the entire head of the wearer, except for the face opening, and to provide such helmet with an integral neck 20 covering portion and with integral throat protecting tabs which are adapted to cross over the chin and around the throat of the wearer and to be secured at the back. Any suitable fastening means may be used, but 25 we prefer to use tying strings, as shown in the drawings.

In the drawings, Figure 1 is a perspective view of the helmet;

Fig. 2 a rear view;

30 Fig. 3 a side elevation;

Fig. 4 a front elevation showing the helmet in use; and

Fig. 5 a rear view of the tabs in use.

Referring to the various parts by numbers, 1 designates the top or dome part 35 of the helmet, and 2 the neck portion thereof. 3 designates the face opening, and 4 the throat protecting tabs which are formed integral with the neck portion. The helmet

40 is made up of a rear section 5; two side sections 6, and a short front dome part 7. The rear section and side sections extend from the bottom of the neck portion to the top of the dome, and the throat protecting tabs are 45 integral with the lower part of the side sections and extend forwardly therefrom, as shown clearly in Figs. 1 and 3. The helmet may be made of any suitable material; we have used successfully a warm felted fabric.

50 Secured to the ends of the throat protecting tabs are tying strings 8; and the edges of the helmet are bound by a binding tape 9.

In use the helmet is pulled down over the

head of the wearer, as indicated in Fig. 4, and the throat protecting tabs are crossed 55 over the chin and carried around the throat, the tying strings being secured together in the back, as shown clearly in Fig. 5. The throat tabs 4 are each formed just sufficiently long to extend rearwardly and only partly 60 encircle the neck of the wearer in such a manner as to reduce to the minimum the amount and bulk of material about the neck, thus allowing perfect freedom of movement of the head and neck of the wearer, which is 65 essential to the strenuous and active life of a soldier. The helmet is formed of a sufficiently warm material, and the neck portion 2 thereof extends downwardly well over the shoulders of the wearer, so that a number 70 of wrappings of the tabs 4 about the neck is unnecessary to provide the required protection. The tying strings 8 eliminate the necessity of tying the ends of the tabs themselves together, which would produce a large 75 and uncomfortable, as well as hampering, amount of material about the neck. The tying strings further provide a fastening means which can be easily and quickly manipulated by the wearer, even when the 80 hands are numb or cold, while were the tabs connected by buttons or the like, manipulation thereof would be difficult and frequently impossible were the hands of the wearer cold or numb. When in position the helmet 85 is securely fastened, and any superposed headgear, such as a shrapnel helmet or other hat, may be placed over the helmet, and when said outer headgear is removed the trench helmet remains securely in position. 90 It will, of course, be understood that the throat tabs may be longer or shorter, as desired, and that other forms of fastening means may be substituted for the tying strings; it being desirable, however, that the 95 securing means be at the back of the helmet in order that they shall be out of the way of the wearer, and that there will be nothing in front liable to catch in the projecting parts of the gun or other device with which 100 the wearer is working.

What we claim is:

1. A trench helmet formed with a face opening and comprising a dome part, a neck portion integral therewith and of a length 105 sufficient to extend downwardly well over

the shoulders of the wearer, forwardly extending throat protecting tabs integral with the neck portion and at the lower part of the face opening adapted to be crossed over the chin of the wearer and carried rearwardly around the neck, each of said tabs being of a length sufficient to extend only partially around the neck so as not to overlap at the rear, and means for securing the ends of the said throat tabs at the rear of the helmet.

2. A trench helmet formed with a face opening and comprising a dome part, a neck portion integral therewith and of a length sufficient to extend downwardly well over the shoulders of the wearer, forwardly extending throat protecting tabs integral with the neck portion and at the lower part of the face opening adapted to be crossed over the chin of the wearer and carried rearwardly around the neck, each of said tabs being of a length sufficient to extend only partially around the neck so as not to overlap at the rear, and a tying string secured to the extremity of each of said tabs for fastening

the ends of the tabs together at the rear of 25 the helmet.

3. A trench helmet formed with a face opening and comprising a dome part and a neck portion and formed of a rear section, two side sections and a front portion, the rear and side sections extending from the top of the dome part to the lower edge of the neck portion, the front portion extending from the top of the dome part to the upper edge of the face opening, forwardly 30 extending throat protecting tabs formed integral with the lower neck portions of the side sections said throat protecting tabs being adapted to be crossed over the chin and carried around the throat of the wearer, and 35 means connected to the ends of said tabs adapted to be connected together at the back of the wearer.

In testimony whereof we hereunto affix our signatures this 26 day of January, 1918. 40

WILLIAM E. WEBB, JR.
GEORGE L. CLOSE.
